UNITED STATES PATENT OFFICE.

GEORGE R. COLLINS, OF CHICAGO, ILLINOIS.

DESIGN FOR A COSMETIC JAR.

Application filed May 19, 1924. Serial No. 9,652. Term of patent 14 years.

To all whom it may concern:

Be it known that I, GEORGE R. COLLINS, a citizen of the United States, residing in the city of Chicago, county of Cook, and State of Illinois, have invented a new, original, and ornamental Design for Cosmetic Jars, of which the following is a specification, reference being had to the accompanying drawing, forming part hereof.

The figure is a perspective view of a cosmetic jar, showing my new design.

I claim:

The ornamental design for a cosmetic jar as shown.

GEORGE R. COLLINS.
